UNITED STATES PATENT OFFICE.

JOHN SCHULTZ, OF NEW BRITAIN, CONNECTICUT.

ELECTRIC LAMP.

Application filed December 7, 1923. Serial No. 679,146.

To all whom it may concern:

Be it known that I, JOHN SCHULTZ, citizen of the United States, residing at New Britain, in the county of Hartford and State of Connecticut, have invented certain new and useful Improvements in Electric Lamps, of which the following is a specification.

This invention relates to the art of illumination and has particular reference to an improved form of electric lamp adapted for many uses, such as a hand illuminating signal, a side or dash lamp for automobiles, a trouble lamp, or the like.

The primary object of the invention is to provide a lamp of the above kind which embraces the desired qualities of simplicity and durability of construction, as well as efficiency in operation.

Another object of the invention is to provide a hand illuminating signal lamp of improved construction, having a switch so arranged and constructed as to permit the same being manipulated for lighting the lamp with facility and ease through operation of the user's thumb when the lamp is supported against the rear side of and by the index and middle fingers of the user's hand.

Still another object of the invention is to provide improved means for supporting the lamp against the rear side of and from the index and middle fingers of the user's hands, and means cooperating with a member of said supporting means for mounting the lamp upon the side or sash of a motor vehicle, whereby the lamp may serve the useful purpose of a side light or dash board light.

Other objects will appear as the nature of the invention is better understood, and the same consists in the novel form, combination, and arrangement of parts hereinafter more fully described, shown in the accompanying drawings, and claimed.

In the drawings, wherein like reference characters indicate corresponding parts throughout the several views:

Figure 1 is an elevational view illustrating a lamp constructed in accordance with the present invention applied to the index and middle fingers of the hand.

Figure 2 is an enlarged view, partly in elevation, and partly in section of the device shown in Figure 1, the lens plate being removed and its retaining ring being in place. 55

Figure 3 is a rear elevational view of the device, shown in Figure 2,

Figure 4 is a side elevational view thereof, looking at the inner side of the lamp casing,

Figure 5 is a view similar to Figure 4, 60 looking at the other side of the lamp casing and with parts broken away and in section.

Figure 6 is an enlarged fragmentary vertical sectional view showing details of the switch construction. 65

Figure 7 is a top plan view of the device shown in Figure 4,

Figure 8 is a side elevational view showing the lamp applied to a bracket for acting as a side or dash lamp for vehicles. 70

Figure 9 is a substantially transverse sectional view taken upon the line 9—9 of Figure 6 and drawn on a smaller scale.

Referring more in detail to the drawings, the lamp embodies a cup shaped casing 5, that is open at its front end and that has its wall enlarged and formed at this end to provide a bead 6 for seating reception of a lens plate 7 that is retained in place by a conventional form of resilient split ring 8 seated within said bead 6 against the margin of the plate 7. The closure or lens plate 7 is preferably of red glass or celluloid for signalling purposes, and as shown clearly in Figure 5, the outer side of the casing 5 is formed with a relatively large window or opening 9 that is closed by means of plain glass or celluloid as at 10. 85

Extending through and secured within an opening in the upper portion of the casing 5 is a sleeve 11 that is inclined inwardly as shown in Figures 1 and 2, so as to extend toward the thumb of the user's hand when employed as a hand signal as shown in Figure 1, and that is also inclined forwardly toward the thumb at its upper end as shown in Figures 4, 5, and 8. The inner end of the sleeve 11 within the casing 5 is slotted in the usual manner as generally indicated at 12 for detachable connection with the base of an electric lamp 13. Fitted within the upper end of the sleeve 11 is a plug member 90 95 100

14, of insulating material and forming the body of a combined connector and switch, which plug is provided upon the bottom thereof with the usual spring projected contact pins 15, adapted for engagement with the contacts on the base of the electric lamp 13, as shown in Figure 6. The plug member 14 is provided with a peripheral groove, as at 16, in which is disposed the circular 10 end portion 17 of a reinforcing spring 18 that is coiled about the feed wires 19 for the lamp 13 in a well known manner, which coil spring 18 protects the feed wires from wear where they project into the sleeve 11, 15 the circular portion of said spring entering groove 16 of the plug 9 for holding said feed wires so as to relieve them against pulling strains which would ordinarily cause their withdrawal from the plugs 14. Fitted 20 within suitable sockets in the plug member 14 are fixed bushings 19 and 20 disposed beside openings provided in said plug 14, into which the feed wires are adapted to be positioned, and threaded through the sleeve 25 and into the plug member 14 are screws 21 and 22 that serve to clamp the feed wires into engagement with said bushings 19 and 20 for effecting electrical connection therewith. The bushing 19 may be electrically connected with its contact 15, through the medium of the projecting spring thereof, while the bushing 20 is normally disconnected, electrically, from the contact 15 of the same. The upper end of the 30 sleeve 11 is closed by means of a cap 23, that is retained in place by means of a screw 22, and through which projects a longitudinally movable switch element or rod 24 that is slidably disposed through the bushing 20, and that has a knob or finger piece 25 upon its upper or outer end. The switch rod 24 is normally projected upwardly or outwardly by means of a spring 26, and the spring of the contact 15 disposed in 35 alignment with the switch rod 24 bears against a contact plate 27 disposed in line with the inner end of the switch rod 24 as shown in Figure 6. The spring 26 normally holds the switch rod 24 out of contact with the contact plate 27 and upon 40 inward movement of said switch rod 24 the latter is engaged with the contact plate 27, so as to close the circuit to the lamp 13. A hollow slide 28 may be carried by the cap 50 23 for maintaining the switch rod 24 in circuit closing or depressed position. The important feature of this switch construction is that the switch rod 24 is movable longitudinally of the sleeve 11 and exposed 55 at the upper end of the latter in position to be engaged by the thumb of the user when the device is attached to the back of the index and fourth fingers of the user's hand as shown in Figure 1, the slide 28 being movable obliquely to the longitudinal axis of

the lamp casing 5 as indicated by position of these parts as shown in Figure 7, so that upon flexing of these thumbs, the slide 28 may be properly manipulated. In other words, when the thumb is depressed, the outer joint thereof naturally moves in this oblique direction, so that the slide 28 may be conveniently moved over the switch rod 24 for maintaining the latter in circuit closing position. 75

Attached to the back of the casing 5 is an elongated plate 29 that is vertically arranged when in use, and this plate has its ends outturned to provide flanges 30, an intermediate flange 31 being stamped outwardly from the intermediate portions of the plate 29, and all of said flanges 30 and 31 being provided with elongated slots as indicated at 32 in Figure 7, that are in alignment with each other. An adjustable elastic strap has its upper end attached to the upper flange 30 and is slidably threaded through the slot in the intermediate flange 31, as well as the lower flange 30 as shown clearly in Figures 3 and 4. In this manner, two looped portions may be formed in the elastic strap, which is indicated at 33, for embracing the index and forefingers of the user's hand so as to effectively secure the lamp to said fingers and against the back 80 of the same. The adjustable nature of the elastic strap 32 permits of applying the device to fingers of different sizes. 85

As shown clearly in Figure 3, the longitudinal axis of the plate 29 is angularly 100 related to the longitudinal axis of the sleeve 11, so that when the device is attached to the hand, the sleeve 11 inclines upwardly and inwardly so that the switch rod 24 is properly positioned for engagement by the 105 thumb of the hand.

In the use of the device as a signal lamp, the lamp is attached to the fingers as specified above, and when the hand is extended above the side of the vehicle by the driver, 110 he may apply a pressure upon the switch rod 24 so as to cause the lamp 13 to be lighted, and the light from this lamp will shine through the red colored lens plate 7, as well as outwardly through the window 9 115 for presenting a danger signal and illuminating the hand of the driver. The signal will thus be effective in preventing accidents and it will thus be apparent that the device may be also employed as a trouble lamp by 120 reason of the light shining through the window 9.

The slot 32 in the flanges 30 and 31 are 125 relatively wide, so as to accommodate the vertical upstanding member 34, of an angular sheet metal bracket 35, that is attached by means of screws or the like 36 to the desired part of the motor vehicle. The intermediate portion of the bracket 35 will thus act as a supporting medium for the 130

lamp to rest upon when the end portion 34 is disposed through the aligned slots 32 of the flanges 30 and 31, and the lens plate 7 will be presented toward the dash board or 5 side of the vehicle, so that the light will shine in the proper direction through the side of the casing as allowed by the window 9. When the bracket 35 is attached to the dash board, the lamp will serve effectively, 10 as a dash light, while when the bracket is attached to the side of the vehicle, a device will effectively provide a side vehicle light. By providing the slide teeth 28, the lamp may be maintained lit without requiring 15 holding of the switch rod 24 in depressed position by the operator.

It will thus be seen that I have provided a simple, durable and efficient form of lamp that may be usefully employed for many 20 purposes, and that may be cheaply and easily constructed as well as placed into use.

What I claim as new is:

1. In a hand signal and illuminating lamp 25 of the character described, a substantially cup-shaped casing having its opened ends or front provided with a closure plate or lens, means carried by the back of the lamp casing for attaching the lamp casing to the 30 back of the index and middle fingers of the hand, and a switch carried by the lamp casing including a depressible switch element exposed at the top of the lamp casing in position to be depressed by the user's thumb 35 when the lamp is attached to said fingers.

2. A signal and illuminating lamp of the character described comprising a lamp casing of cup shape having its open end closed by means of a lens plate, a tube extending 40 through the top of the casing and having means upon its inner end within the inner casing for detachable supporting engagement with the base of an electric lamp, a switch including a plug fitted within the 45 upper end of said sleeve, said switch further embodying a longitudinally movable switch rod normally in circuit breaking position and depressible longitudinally of the sleeve for closing a circuit, said switch rod being 50 exposed at the upper end of the sleeve, and means to attach the back of the lamp casing against the back of the index and forefingers of the user's hand with the switch carrying sleeve inclined upwardly and in- 55 wardly toward the user's thumb, said sleeve being also inclined upwardly and toward the back of the lamp casing for facilitating engagement of the switch rod by the thumb, the means for attaching the lamp by the 60 fingers comprising a vertical plate fixed to the back of the lamp casing and having vertically aligned slotted flanges and an adjustable elastic band threaded through the slots of said flanges.

3. A signal and illuminating lamp of the

character described comprising a lamp casing of cup shape having its open end closed by means of a lens plate, a tube extending through the top of the casing and having means upon its inner end within the inner casing for detachable supporting engagement with the base of an electric lamp, a switch including a plug fitted within the upper end of said sleeve, said switch further embodying a longitudinally movable 70 switch rod normally in circuit breaking position and depressible longitudinally of the sleeve for closing a circuit, said switch rod being exposed at the upper end of the sleeve, and means to attach the back of the lamp casing against the back of the index and forefingers of the user's hand with the switch carrying sleeve inclined upwardly and inwardly toward the user's thumb, said sleeve being also inclined upwardly and toward the back of the lamp casing for facilitating engagement of the switch rod by the thumb, the means for attaching the lamp by the fingers comprising a vertical plate fixed to the back of the lamp casing and having vertically aligned slotted flanges, and an adjustable elastic band threaded through the slots of said flanges, and a bracket including an upstanding member 75

positionable through the slots of the plate for supporting the lamp casing at the side or from the dash board of a vehicle with the closure plate presented toward the side or dash board of said vehicle, said lamp casing having a window in a side thereof, said bracket further including a horizontal lower

and intermediate portion upon which the lamp casing is adapted to rest when the upstanding member of said bracket is positioned through the slots of the plate flanges.

In testimony whereof I affix my signature.

JOHN SCHULTZ.
